UNITED STATES PATENT OFFICE.

BALDWIN H. KANNENBERG, OF CHICAGO, ILLINOIS, ASSIGNOR TO AMERICAN CAN COMPANY, OF NEW YORK, N. Y., A CORPORATION OF NEW JERSEY.

REMOVABLE-COVER SHEET-METAL CAN.

No. 893,630.

Specification of Letters Patent.

Patented July 21, 1908.

Application filed September 15, 1906. Serial No. 334,794.

To all whom it may concern:

Be it known that I, BALDWIN H. KANNENBERG, a citizen of the United States, residing in Chicago, in the county of Cook and State of Illinois, have invented a new and useful Improvement in Removable-Cover Sheet-Metal Cans, of which the following is a specification.

My invention relates to improvements in sheet metal pails having removable covers.

The object of my invention is to provide a bailed pail with removable cover, of a simple, strong, efficient and durable construction, suitable for use as a shipping package for lard and other articles, in which the removable cover may be tightly and firmly secured upon the pail so that the pail may be used as a shipping package without the necessity of crating, and in which the cover may at the same time be conveniently removed when it is desired to open the package and again replaced for the temporary closing of the package while its contents are being used, and in which the removable cover will not only tightly close the package but also serve to brace and stiffen the upper end of the body of the pail against collapse when the large heavy pail is lifted by the handle in shipment or handling.

My invention consists in the means I employ to practically accomplish this object or result. That is to say, it consists in the novel construction of parts and devices, and in the novel combinations of parts and devices herein shown and described.

In the accompanying drawing forming a part of this specification, Figure 1 is a central vertical section through the bail ears of a sheet metal pail embodying my invention. Fig. 2 is a detail partial elevation and Fig. 3 is a detail partial plan view.

In the drawing, A represents the sheet metal body of the pail, B the cover, C the lower or bottom head, D the bail ears and F the bail.

The body A of the pail may be of any suitable construction, but is preferably of slightly conical or tapering form, as illustrated in the drawing. The bottom head C is preferably furnished with a deep countersink c and is secured to the lower end of the body A by any suitable seam c¹. The body A is preferably furnished with an annular bead a to stiffen and strengthen the lower end of the body.

At its upper or mouth end, the body A of the pail is furnished or preferably furnished with a curled edge or roll a¹ forming an external annular shoulder at the upper end of the body which serves not only to strengthen and stiffen the body, but also as an external shoulder for the shoulders d of the bail ears D to fit against or engage. This annular roll or shoulder a¹ upon the upper end of the can body also serves as a seat for the annular roll or rim b of the cover B to fit against.

The cover B has an outer deep upright but slightly tapering or flaring annular flange or wall b¹ which fits snugly within and engages the slightly tapering or flaring mouth a² of the can body A so as to effect a tight closure of the pail by reason of the tight friction fit of the annular flange or wall b¹ of the cover B within the mouth or wall a² of the body of the pail. The cover B also preferably has an upwardly projecting flange or wall b² forming a deep annular channel or groove b³ between the same and the outer annular flange or wall b¹. The cover B also has a horizontal or outwardly projecting flange b⁴, the outer edge of which terminates in an inward curve or roll b forming the annular shoulder before mentioned of the cover B, which fits upon and against the annular roll or shoulder a¹ at the upper end of the body of the pail.

The ears D are of sheet metal and are securely attached to the body of the pail by rivets d¹ or other suitable means. Each of these bail ears is provided with an outwardly projecting flange or shoulder d which fits under the annular roll or shoulder a¹ on the body of the pail so that these interengaging shoulders on the pail body and ear will serve to relieve the rivets d¹ from strain, and thus afford a stronger and more secure attachment of the bail ears to the body of the pail. Each of the bail ears has an upwardly projecting lug or member d⁵ furnished with an eye d² to receive the pivot hook f of the bail F, and each of the bail ears is further provided with one or more, preferably two integral clenching lips d³, preferably one on each side of the straight bail-eye lug d⁵ and separated therefrom by upright slits d⁴. These integral lips d³ on the bail ear are adapted to be bent or clenched down over the rim of the cover B when the cover is pressed home on the body of the pail, thus

securely locking and holding the cover in place and in tight firm engagement with the upper end or mouth of the pail, so as to effect a tight closure and so as to cause the cover 5 to effectually brace, stiffen and strengthen the upper end of the body of the pail, and so as to cause the two annular rolls *a*¹ on the pail body and *b* on the cover to mutually coact with each other in bracing and stiffening 10 the upper end of the covered pail as a whole; so that the pail when made of the customary large size used for shipping lard or other like heavy materials and filled therewith, may be lifted by the bail in shipment or handling 15 without danger of collapsing or injuring the package or breaking off the bail ears. By this means, I am enabled to produce at comparatively small cost of manufacture, a strong, efficient and durable shipping package 20 for lard or other heavy materials, and one which will also serve as a useful pail or household utensil after the goods contained therein have been consumed, and also a shipping package suitable for shipment without crating. 25

I claim:—

1. A sheet metal shipping package for lard or other materials, comprising in combination a body having a slightly flaring or tapering mouth furnished with an external annular curled edge or roll at its upper end, a removable cover having an outer flange or wall fitting within the flaring mouth of the body and furnished with an outwardly projecting 30 annular roll or shoulder engaging the annular roll or shoulder at the upper end of the pail body, and bail ears secured to said body and having shoulders engaging said external shoulder on said body, and provided with a 35 bail eye lug projecting above the cover and with clenching lips on each side of said lug and separated therefrom by slits, said clenching lips coöperating with said shoulders on 40

the bail ear and body to securely clamp the cover in place, substantially as specified. 45

2. In a sheet metal pail, the combination with a body having an annular shoulder at its upper end, of an inside fitting cover having an annular shoulder or rim engaging the annular shoulder on the pail body, and bail 50 ears having bail eye lugs projecting above the cover, said bail ears being provided with integral clenching lips at the side of said lugs and separated therefrom by slits for locking the cover in place, substantially as specified. 55

3. The combination with a sheet metal body having an annular exterior shoulder at its upper end, of a cover and bail ears secured to said body and provided each with a bail eye lug projecting above the cover and with 60 integral cover holding lips at the side of said lugs and separated therefrom by slits, said bail ears having shoulders fitting under and engaging said external shoulder on the pail body, substantially as specified. 65

4. The combination with a sheet metal body having an annular external shoulder at its upper end, of a cover, and bail ears secured to said body and provided each with a bail eye lug projecting above the cover and 70 with an integral clenching lip, said bail ears having shoulders fitting under and engaging the external annular shoulder on said body, substantially as specified.

5. The combination with a cover of a vessel body having an external shoulder of bail ears secured thereto and provided with shoulders engaging said external shoulder on the body, said bail ears having bail eye lugs projecting above the cover, and clenching lips on 80 each of said lugs and separated therefrom by slits, substantially as specified. 75
